UNITED STATES PATENT OFFICE.

THEODORE SHAPIRO, OF BROOKLYN, NEW YORK, ASSIGNOR TO ARTCRAFT METAL STAMPING CORPORATION, OF BROOKLYN, NEW YORK, A CORPORATION OF NEW YORK.

DESIGN FOR A LIGHTING FIXTURE.

Application filed October 20, 1927. Serial No. 23,821. Term of patent 3½ years.

To all whom it may concern:

Be it known that I, THEODORE SHAPIRO, a citizen of the United States, residing at Brooklyn, in the county of Kings and State of New York, have invented a new, original, and ornamental Design for a Lighting Fixture, of which the following is a specification, reference being had to the accompanying drawing, forming a part thereof, in which the figure is a front view, slightly in perspective, showing my new design.

I claim:

The ornamental design for a lighting fixture as shown.

THEODORE SHAPIRO.
